UNITED STATES PATENT OFFICE.

WILLIAM PARKIN, OF TAUNTON, MASSACHUSETTS, ASSIGNOR TO REED & BARTON, OF SAME PLACE.

DESIGN FOR A TEA-SERVICE.

Specification forming part of Design No. 5,873, dated May 21, 1872.

To all persons to whom these presents may come:
Be it known that I, WILLIAM PARKIN, of Taunton, of the county of Bristol and State of Massachusetts, have invented a new and useful and ornamental Design or Configuration for a Tea Service or Pot; and do hereby declare the same to be described as follows and represented in the accompanying drawing, of which—

Figure 1 is a side elevation, and Fig. 2 a front view, of a tea-pot made in accordance with said design.

The main part of the body A of the tea-pot is essentially cubical, with rounded edges, and having an inverted dome-shaped bottom, *a*, and tapering and truncated dome-shaped top *b*, all as shown. From each side of the body there projects a raised, square, or rectangular panel, *c*, which may be either plain or ornamented. The cover *d* is a pyramidal dome, its

vertical transverse section being parabolical in shape. It is surmounted by an ornamental knob, *e*, formed as represented. The nose and handle are exhibited at *f* and *g*, they having the configurations, as shown. Each leg *h*, of which there are four, has on it a human head or face, in full relief, surmounted by a crown, out of which spring a collection of trefoils, all being as represented.

I claim—

In the said tea-pot the ornamental design or configuration of the body, also that of the handle, that of the nose, that of the leg, and that of the lid or cover and its knob, all being as represented.

WILLIAM PARKIN.
